P. H. BAKER.
REFRIGERATOR.
APPLICATION FILED JUNE 16, 1916.

1,275,828.

Patented Aug. 13, 1918.

Inventor:

Philip H. Baker,
his Attorney

UNITED STATES PATENT OFFICE.

PHILIP H. BAKER, OF CLEVELAND, OHIO.

REFRIGERATOR.

1,275,828.

Specification of Letters Patent. Patented Aug. 13, 1918.

Application filed June 16, 1916. Serial No. 104,103.

To all whom it may concern:

Be it known that I, PHILIP H. BAKER, a citizen of the United States, resident of Cleveland, county of Cuyahoga, and State of Ohio, have invented a new and useful Improvement in Refrigerators, of which the following is a specification, the principle of the invention being herein explained and the best mode in which I have contemplated applying that principle, so as to distinguish it from other inventions.

My invention relates to refrigerators and particularly to refrigerators adapted for use in the storing of ice cream in brick form.

The object of the invention is to provide a refrigerator for the above described purpose which will be economical of construction and efficient in the performance of its function.

Heretofore it has been customary to store ice cream which was previously formed into bricks and wrapped in a suitable envelop, in a cylindrical can having a removable top or cover, the said can being set into the interior of a receptacle or cabinet of suitable size having a top provided with a hinged cover, the ice being packed around same up to, as nearly as possible, the top of the can. Salt is used in connection with the ice to maintain the temperature at a sufficiently low point to permit the cream to retain its solidity. In this method of storage, however, and inasmuch as much ice is kept in the receptacle as is possible without covering the top, there is always present the possibility of ice or salt entering the top of the can when the latter is open, thus threatening and sometimes bringing about the destruction of some, if not all, of the contents of the can. Furthermore, it was found to be more or less difficult to gain access to the contents of the can and readily remove same therefrom.

A specific object of my invention is to provide a refrigerator by means of which there can be no possibility of access of the ice or salt to the ice cream and which will render it easy to store or remove the bricks.

The annexed drawing and the following description set forth in detail certain means embodying my invention, the disclosed means, however, constituting but one of various mechanical forms in which the principle of the invention may be applied.

In said annexed drawing:—

Figure 1 represents a front elevation,

showing the front door open, of a refrigerator embodying my invention.

Fig. 2 represents a vertical transverse central cross-section of the refrigerator also showing the door in its open position.

Fig. 3 represents a horizontal section taken upon the plane indicated by line III—III in Fig. 1.

Fig. 4 represents a detail section, upon an enlarged scale, taken upon the plane indicated by a line IV—IV in Fig. 1, and

Fig. 5 represents a similar detail section taken upon the plane indicated by line V—V in Fig. 1.

The illustrated embodiment of my invention comprises a main receptacle 1 which is built up out of wood, upright corner pieces 2, front intermediate upright pieces 3 and upper and lower transverse pieces 4 forming the main frame. The spaces between these frame members are filled with a suitable insulation 6 in the form of integral slabs of cork composition or other suitable material. A suitable facing 7 is secured to the outside of this frame and a suitable pedestal 8 is provided as shown clearly in Figs. 1 and 2. The top of the receptacle is open and provided with a hinged door 9 for closing such opening. The inner space 10 thus formed is lined with a zinc lining 11 made up of plates suitably soldered together. This zinc lining is open at the top, the said opening registering with the opening of the receptacle, and an angular zinc facing 12 covers the upper edge of the zinc lining, being secured at the sides by means of suitable nails 13, the upper portion being held by the upper facing members 14 of the receptacle. A drain pipe 15 at the bottom projects through the zinc lining and permits the liquid to drain off, as will be readily understood, this pipe being connected in any suitable manner to render the connection proof against leakage.

The front of the receptacle is provided with an opening 16 and the front of the zinc lining with a similar opening 17 in register with the said opening 16. Secured, preferably by soldering, to the portion of the lining adjacent to the opening 17, is a rectangular structure 18 having a front opening registering with the opening 17, the walls of the structure projecting into the space 10 of the main receptacle and forming an interior compartment 19 for the reception of the bricks of ice cream. The bottom of said compartment is removed a distance

from the bottom of the interior of the main receptacle so that ice and cold brine may be placed beneath it. The width of this compartment 19 is, as shown in Fig. 3, less than that of the interior 10 of the receptacle, and the top of the compartment somewhat below the cover 9. By reason of this construction it will be seen that ice and cold brine may be constantly kept in contact with the five sides of the compartment and keep its interior in a thoroughly cooled condition.

The bottom of the compartment 19 is preferably lower than the sill 20 of the front opening 16 and in this bottom portion may be placed longitudinal wooden members 21 and transverse members 22 forming a base upon which the contents of the compartment may rest.

The sides of the opening 16 are lined with a zinc angular lining 23 secured with nails, said lining projecting slightly into the compartment 19, as shown in Fig. 2, the outer part of the angular lining being held by the front facing member 7.

The inner end of the walls of the compartment 19 are supported by means of a suitable support 24, as shown in Fig. 2. A suitable hinged door 25 is provided for closing the opening 16 and a suitable locking device is provided for retaining same in its closed position.

The ice and salt are charged into the top of the device and thoroughly packed around the compartment 19. The ice cream bricks are placed in said compartment and are al-

ways entirely out of contact with the ice and brine and at no time may the latter have access thereto. The opening 16 being placed in the front, renders the contents readily accessible, as will be noted.

When for any reason it may be desired to repair the interior lining 11, the angular strips 12 and 23 may be removed by withdrawing the nails, whereupon the entire lining, together with the attached walls of the compartment 19, may be lifted up and out of the receptacle.

Having fully described my invention, what I claim and desire to secure by Letters Patent is:—

A refrigerator comprising an inclosing structure having a top opening and a side opening; closures for said openings; an interior lining of sheet metal for said structure having an opening registering with said top opening; an open sided sheet metal structure secured to said lining with its opening registering with the side opening in said casing, said sheet metal structure projecting within said lining; a metal facing secured to the top edge of said lining with its upper portion disposed under and secured by the top of the inclosing structure; and a metal lining for the side opening of said inclosing structure, projecting into said sheet metal structure; and secured by side members of said inclosing structure.

Signed by me, this 15th day of June, 1916.

PHILIP H. BAKER.
